US00D945428S

(12) **United States Design Patent** (10) Patent No.: **US D945,428 S**
(45) Date of Patent: **** Mar. 8, 2022**

(54) **PROTECTIVE COVER FOR COMPUTER HARDWARE**

(71) Applicant: **Haitao Xu**, Guangdong (CN)

(72) Inventor: **Haitao Xu**, Guangdong (CN)

(**) Term: **15 Years**

(21) Appl. No.: **29/709,595**

(22) Filed: **Oct. 16, 2019**

(51) LOC (13) Cl. **08-07**

(52) U.S. Cl.

USPC **D14/440; D14/447**
